fornia

Filed May 23, 1966, Ser. No. 2,376

Term of patent 14 years

(Cl. D48—31)

FIG. 3

FIG. 5

FIG. 4

FIG. 1 is a top plan of the fixture.
 FIG. 2 is a side elevation of the fixture.
 FIG. 3 is a bottom plan view of the same.
 FIG. 4 is a view of the fixture taken from its inner end.
 FIG. 5 is a view of the fixture taken from its outer end.
 The dominant features of my design reside in the portions shown in full lines. The broken line showing of a support pole in FIGS. 1, 2, 3 and 4 is for illustrative purposes only.

I claim:

The ornamental design for an outdoor lighting fixture, as shown and described.
